UNITED STATES PATENT OFFICE.

WALTER HAHNEMANN AND LEONID ADELMANN, OF KITZEBERG, NEAR KIEL, AND HUGO LICHTE, OF KIEL, GERMANY, ASSIGNEES TO THE FIRM SIGNAL GESELLSCHAFT M. B. H., OF KIEL, GERMANY.

ARRANGEMENT FOR ELIMINATING DISTURBANCES IN SOUND SIGNALING.

Application filed February 4, 1921, Serial No. 442,589, and in Germany January 25, 1917.

The devices used for the reception of sound signals usually comprise a sound collecting or absorbing member, such as a diaphragm that responds to sound vibrations, and a member 5 that serves to receive the absorbed sound energy, such as a microphone. In such devices the latter member may be associated with a vibratory body or structure, such as a tuning fork or the like.

10 Receiving apparatus of this kind are usually tuned as a whole to the frequency used for signaling. Although the tuning increases the sensitiveness of the receiver, it is accompanied by the disadvantage that whenever the 15 apparatus is excited by shocks, due to mechanical or acoustic disturbances, sounds are heard in the apparatus that correspond to the frequency for which the apparatus is tuned, so that its receiving function is seriously interfered with. If the expedient of tuning is entirely dispensed with, or if the receiving apparatus as a whole is tuned to a frequency that differs very much from the signaling frequency, the sensitiveness of the apparatus to 20 the sound signals employed will be considerably impaired.

The object of the invention is to provide a receiving apparatus of this kind which is sufficiently sensitive to sounds whose rate of vibration corresponds to the actual signaling frequency, but which is affected by disturbing sounds or noises to the smallest possible extent.

The invention relates more particularly to receiving apparatus which comprise a system 35 consisting of two or more vibratory structures or bodies coupled to each other, and in which one of the structures or members of the system, which structure or member may consist of a diaphragm, a piston, the hull of a ship, or the 40 like, assumes the function of collecting or taking in energy that arrives through the propagating medium (water, air), while another member of the system that acts as the receiver proper, and may take the form of a microphone or an electromagnetic detector, assumes the function of converting the sound energy into electrical energy that may be made perceptible by the human ear with the aid of an instrument such as a telephone receiver.

50 The invention consists in general in so tuning the various vibratory bodies or structures of which the apparatus is composed that after due allowance is made for the effect produced

on each vibratory body by its being coupled to another, any one of the plurality of frequencies of resonance which the composite vibratory apparatus will possess, will coincide with the frequency used for signaling, barring the particular frequency which corresponds to that of the vibratory receiving structure proper, i. e. that of the microphone or the like.

The purport of this will be explained by the following description with reference to the accompanying drawings in which

Fig. 1 shows the resonance curves obtained 65 from a diaphragm alone, a microphone alone and the resultant curve when the diaphragm and microphone are coupled together;

Fig. 2 shows the resonance curve of a coupled system in which the diaphragm is more 70 highly damped than the microphone;

Fig. 3 shows the resonance curve of a coupled system in which the resonance peak corresponding to the natural frequency of the diaphragm coincides with the signaling frequency and the peak corresponding to the natural frequency of the microphone is so far removed from the signaling frequency as to have little effect on the functioning of the coupled system; and

Fig. 4 shows a sectional view of a practical example of a sound receiver constructed according to the invention.

If in a composite vibratory apparatus or system comprising two vibratory structures 85 coupled to each other, each individual structure has its own frequency of resonance, the behaviour of the system when subjected to vibrations will be such that each of the individual vibratory structures will exhibit two 90 frequencies of resonance and these two frequencies will be the same in each structure. One of them will, however, be lower and the other higher than the frequencies of resonance of the individual structures when separated from each other, and the effect produced in each structure will be greatest at the particular frequency of resonance that belongs to its own natural rate of vibration.

Hence in accordance with the invention, in 100 receiving apparatus comprising a collecting member that takes in the energy and an energy transferring or converting member, these vibratory members are so tuned and coupled as to bring about a coincidence between the particular post-coupling frequency 105

of resonance (i. e. the frequency at which resonance is obtained after the different vibratory structures are coupled to each other) that belongs to the natural rate of vibration 5 of the collecting member and the frequency used for signaling, but not between the signaling frequency and the post-coupling frequency of resonance that corresponds to the natural rate of vibration of the said transferring member.

In Fig. 1, in which the abscissæ designate the frequencies while the ordinates designate the amplitudes, the solid graph represents a resonance curve as obtained in the microphone of a receiving apparatus comprising a sound collecting diaphragm coupled to a microphone, the diaphragm being the one vibratory structure and the microphone the other. Of the two post-coupling frequencies of resonance of the coupled structures the most effective one N_1 is associated with the natural rate of vibration of the microphone and the less effective one N_2 is associated with the natural rate of vibration of the diaphragm. 25 The resonance curves of the separate or uncoupled vibratory structures are indicated by a broken line and a dash and dot line, the frequency of resonance of the microphone by itself lying at n_1 , and that of the diaphragm 30 by itself lying at n_2 .

In accordance with the invention N_2 is the frequency that must be selected for signaling with this system. Disturbances which chiefly arise from shocks or vibrations that are practically non-periodic will be transformed in a system of this kind principally into periodical vibrations whose frequency is N_1 , so that signals with a frequency of N_2 will be clearly distinguishable from the disturbing 35 noises. By coupling the two vibratory structures more or less closely the crests of the resonance curves may be shifted more or less apart. This can also be done by making the individual natural rates of vibration of the 40 coupled vibratory structures of the system differ from each other more or less widely.

It will be obvious that this expedient of altering the difference between the post-coupling frequencies of resonance is in itself a 45 very effective means of eliminating disturbances. In accordance with the invention the freedom from disturbances can be considerably enhanced by damping the vibrations of the diaphragm more than the vibrations of the microphone. The resonance curve of a 55 system damped in this way is shown in Fig. 2, in which the same signs of reference are used as in Fig. 1.

Thus in vibratory apparatus comprising a 60 diaphragm coupled with a microphone the post-coupling frequency of resonance of the diaphragm is caused to coincide with the frequency of the sound used for signaling. This is also done in an apparatus comprising a 65 diaphragm, a special vibratory structure and

microphone contacts attached to the vibratory structure. The post-coupling frequency of resonance of the microphone, or of the vibratory structure with its attached microphone, may be made either higher or lower than the 70 signaling frequency. In Figs. 1 and 2, the natural frequency of the microphone, together with its corresponding post-coupling frequency, are below the natural frequency of the diaphragm and the corresponding post-coupling frequency thereof used as the signaling frequency. But a preferred arrangement, particularly in cases of receiving apparatus in which the detector used is a microphone, is one in which the natural note of 80 the microphone is so chosen that the post-coupling frequency corresponding to it is higher than the signaling frequency.

For receivers consisting of a rigid casing, a receiving diaphragm, and a microphone coupled to this latter, it is to be considered as characteristic of the invention that the natural rate of the diaphragm is lower than that of the microphone, so that in the whole apparatus the post-coupling frequency belonging to the diaphragm coincides with the 90 signaling frequency. Preferably the vibratory structures are so tuned that the natural period of the microphone lies above the signaling frequency about twice the amount that 95 the natural period of the diaphragm lies above this frequency, (in practice 20% and 40%). Then the coupling between the two parts is to be so chosen, for example, by suitably distributing the masses over the two 100 parts coupled together, that the post-coupling frequency corresponding to the diaphragm coincides with the signaling frequency. In this way at the same time, a degree of coupling especially advantageous for the efficiency of the receiver may be obtained.

Naturally, it is not absolutely necessary to make coincide with the signaling frequency the post-coupling frequency belonging to the fundamental vibration of the diaphragm, 110 but it is also possible to choose a suitable harmonic of a diaphragm of an essentially lower fundamental vibration.

In Fig. 3 of the accompanying drawings the most favourable relations of tuning for a receiver (casing with diaphragm and microphone) treated according to the invention are represented by the resonance curves of the particular structures of the apparatus. The natural vibration of the diaphragm which, in this case, is identical with its fundamental vibration, is J , the natural vibration of the microphone is Z . By acoustically coupling these vibratory structures together the vibrations are displaced into J' and Z' respectively, which are the frequencies of resonance of the coupled system, J' coinciding with the signaling frequency X . A special advantage obtained by this tuning is that the inconstancy of the natural note of the 120 125 130

microphone ceases to be a factor that greatly affects the efficiency of the receiver.

Figure 4 presents a sectional view of a practical construction of a sound receiver according to the principle previously explained. 5 1 represents the casing to which the resonant diaphragm 2 is clamped by the rivets 5, 5. Mounted on the diaphragm 2 and therefore acoustically coupled with it is the microphone 10 phone 3 in its usual form. The diaphragm 4 of the microphone is coupled to the diaphragm 2 by means of the clamping nut 7. The diaphragm 4 carries one electrode 8 while the casing 6 carries the second electrode 9 15 between which electrodes are the carbon granules 10. The diaphragm 2 is tuned to the desired resonant frequency by proper dimensions of size, thickness and material of the diaphragm. The microphone is also suitably tuned to the desired frequency as explained above.

In order to obviate the necessity of using a microphone, bi-resonant or multi-resonant electro-magnetic contrivances may be used 25 which may be made to act both as sending means or receiving means. In accordance with the invention the frequency of the sound signals employed when receiving with an arrangement of this kind would be one that 30 does not belong to the receiving device proper (energy-converter).

In producing multi-resonant apparatus of this kind each individual vibratory body or structure is preferably tuned by itself to a 35 frequency of resonance which, when it is changed by the effect of the various coupled structures, results in the desired post-coupling frequency of resonance. This is done by using the degree of coupling that has 40 been determined by experiment or calculation to be the proper one. When once the amount by which the frequency of resonance is changed through the influence of the coupling 45 has been ascertained in a trial apparatus, the preferable procedure in tuning each individual vibratory structure will be to substitute the amount of the mass of the cooperating parts to be coupled thereto, that affects its tuning, by attaching a weight of corresponding 50 size to it. In doing this it must be remembered that the vibratory structure that takes in the sound energy from the propagating medium upon which it abuts is also affected by a certain amount of the mass of this 55 medium. In the cases of heavy mediums such as liquids this amount is considerable.

The term "sound radiating member" is used in the claims to define generically a member which takes up vibrations from or imparts 60 vibrations to the sound propagating medium; while the term "energy-converting means" is used to designate generically a device which converts sound energy into another form of energy, for example, into electrical energy, 65 or vice versa.

We claim:

1. In sound signal apparatus, an individually tuned vibratory structure, and an individually tuned energy-converting means, means for coupling said vibratory structure and said energy-converting means together acoustically, and the frequencies of resonance of the coupled system being such that the resonance frequency corresponding to the energy-converting means is substantially different from the sound signal frequency. 70 75

2. In sound signal apparatus, an individually tuned sound radiating member, and an individually tuned energy-converting means, means for coupling said sound radiating member and said energy-converting means together acoustically, and the frequencies of resonance of the coupled system being such that the resonance frequency corresponding to the energy-converting means is substantially different from the sound signal frequency. 80 85

3. In sound signal apparatus, an individually tuned vibratory structure, and an individually tuned microphone, means for coupling said vibratory structure and said microphone together acoustically, and the frequencies of resonance of the coupled system being such that the resonance frequency corresponding to the microphone is substantially different from the sound signal frequency. 90 95

4. In sound signal apparatus, an individually tuned vibratory structure, and an individually tuned energy-converting means, means for coupling said vibratory structure and said energy-converting means together acoustically, and the frequencies of resonance of the coupled system being such that the resonance frequency corresponding to the energy-converting means is substantially higher than the sound signal frequency. 100 105

5. In sound signal apparatus, an individually tuned vibratory structure, and an individually tuned energy-converting means, means for coupling said vibratory structure and said energy converting means together acoustically, and the frequencies of resonance of the coupled system being such that the resonance frequency corresponding to the energy-converting means is substantially different from the sound signal frequency while the resonance frequency corresponding to the vibratory structure substantially coincides with the sound signal frequency. 110 115 120

6. In sound signal apparatus, an individually tuned vibratory structure, and an individually tuned energy-converting means, means for coupling said vibratory structure and said energy-converting means together acoustically, the frequencies of resonance of the coupled system being such that the resonance frequency corresponding to the energy-converting means is substantially different from the sound signal frequency, and 125 130

the damping of the vibratory structure being greater than the damping of the energy-converting means.

7. Multi-resonant sound signal apparatus, comprising a tuned sound radiating diaphragm, means for coupling said diaphragm to a tuned sound detector, the tunings and coupling being such that the frequency of resonance of the coupled system corresponding to the said sound detector is substantially different from the sound signal frequency.

8. Multi-resonant sound signal apparatus, comprising a tuned sound radiating diaphragm, means for coupling said diaphragm to a tuned sound detector, the tunings and the coupling being such that the frequency of resonance of the coupled system corresponding to the said sound detector is substantially different from the sound signal frequency and that the frequency of resonance of the coupled system corresponding to the

said diaphragm substantially coincides with the sound signal frequency.

9. In sound signal apparatus, a vibratory structure individually tuned to certain frequency higher than the sound signal frequency, an energy-converting means individually tuned to a frequency higher than the sound signal frequency by an amount about twice as great as the difference between the sound signal frequency and the vibratory structure frequency, means for coupling said vibratory structure and said energy-converting means together acoustically to such a degree that the resonance frequency of the coupled system corresponding to the energy-converting means is substantially different from the sound signal frequency.

In testimony whereof we affix our signatures.
